Inc., Newark, N. J., a corporation of New York

Application January 26, 1932. Serial No. 588,864

4 Claims. (Cl. 178—17)

This invention relates to telegraph code systems and transmitting apparatus adapted to be operated by perforated tapes, and more specifically to apparatus with which tapes, previously prepared for transmitters adapted to send signals having plus, minus and zero portions, may also be used to transmit universal double current signals, and, conversely, to apparatus with which tapes, previously prepared for transmitters adapted to send signals having plus and minus portions, may also be used to transmit signals of plus, minus and zero portions.

It is, therefore, an object of my invention to provide means for eliminating the zero portion of the three-portion code.

It is a further object to insert the zero portion in converse cases.

It is a still further object to render tapes punched in Wheatstone code and Morse cable code to be used interchangeably in transmitting messages over cable and land lines, respectively.

Other objects of my invention will be obvious and will present themselves hereafter to those familiar with the art upon reading the following description and referring to the accompanying drawings, in which:

Fig. 1a represents a tape perforated for transmitting Morse cable code and, below, the corresponding polarity as applied to the cable at the transmitting line;

Fig. 1b represents a tape perforated for transmitting Wheatstone code and, below, the corresponding polarity as applied to the line;

Fig. 2 shows, schematically, apparatus for the transmission of Wheatstone signals from cable code tape;

Fig. 3 shows, schematically, apparatus for the transmission of cable signals from Wheatstone tape; and

Fig. 4 shows in some detail a step-by-step transmitter and, in addition, a means for causing the transmitter to step two center tape perforations at a time instead of one, when such double stepping is necessary.

The Morse cable code is a three-element code employing for its use positive, negative and zero current portions to the line. The dots are represented by positive current portions to the line, the dashes are represented by negative current portions to the line, and the space intervals are represented by zero current portions to the line. These signals are usually sent by a transmitter which is actuated by a previously prepared tape, as shown in Fig. 1a. On this tape the dot is represented by one perforation above the center

line, the dash is represented by a single perforation below the center line, and the space is represented by the absence of either a dot or a dash perforation. In this tape each impulse is represented by one center hole along the tape so that the letter "A", which consists of a dot, dash, space combination, will be represented on the tape by a perforation above a center hole, a perforation below an immediately following center hole, and no additional perforation associated with a last center hole. The letter "A", therefore, will correspond in length to three consecutive center holes along the perforated tape.

In the Wheatstone code, positive current is transmitted to the line for both dots and dashes, and the dashes are distinguished from the dots by their length, a dash being three times the length of a dot. The spaces are represented by a negative current element being sent to the line. The tape which is used to operate the Wheatstone transmitter represents a dot by a perforation directly above a center hole and a perforation directly below the same center hole, as shown in Fig. 1b. The dash is represented by a perforation above a center hole and a perforation below the center hole immediately following. A space is represented by a center hole alone.

The tape for transmitting the letter "A" in both Wheatstone and Morse cable codes and the signal transmitted from this tape are shown in Figs. 1a and 1b. From the signals that are transmitted, it is evident that in the cable code signal one interval of time is required for transmitting a dot, dash, or space. In the following analysis, it is assumed that the dot, dash and space signals of the Morse cable code are all signals of equal length and that each signal requires an interval of time consisting of two equal elements; it is further assumed that the dot, dash and space signals of the Wheatstone code are not all signals of equal length, e. g., only the first and third signals being of equal length, and, furthermore, that these signals require unequal intervals of time for transmission, namely, two, four and two elements, respectively; and it is also assumed that an element of the Morse cable code is equivalent to an element of the Wheatstone code. It is evident, therefore, that the Wheatstone signal for a dot requires two elements for transmission, that for a space requires two elements, and that for a dash requires four elements. Thus, a Wheatstone dot can be transmitted from a cable code dot by changing the single positive Morse cable code dot signal into

two elements, each occurring for half the time interval required for the transmission of the cable code dot, the first of these elements being positive and the second being negative. A 5 Wheatstone space can be transmitted from a cable code space by converting the single Morse cable code zero signal into two elements both of which are of negative polarity. However, it is more difficult to transmit a Wheatstone dash 10 from a cable code dash, as the Wheatstone dash is four elements long compared to a length of two elements for the Morse cable code dash. Therefore, a Wheatstone dash is twice as long as a cable code dash. But, a Wheatstone dash 15 may be further broken up into two equal intervals of time, one time interval corresponding to two elements of positive polarity, the other time interval corresponding to one element of positive polarity and one element of negative polarity. 20 Thus, a Wheatstone dash, on the basis of the above analysis, is made up of two positive elements plus a Wheatstone dot.

From this analysis it follows that a Wheatstone dot and a Wheatstone space may be transmitted 25 from cable code tape without much difficulty, but, whenever a Wheatstone dash is to be transmitted from cable code tape, it is necessary to stop the tape for a time interval equal to two elements and to supply locally a Wheatstone dot termina- 30 tion during this interval, the dash perforation in the cable code tape transmitting the first two elements of the Wheatstone dash signal and a locally supplied dot termination adding the final positive and negative elements.

35 A continuously rotating transmitter cannot readily be used for the above purpose, as the tape must be halted for a time interval of two elements whenever a Wheatstone dash is to be transmitted from a Morse cable code tape. A step-by-step 40 transmitter, operated in the same manner as those used on multiplex circuits, can, however, be used for this purpose. Such a transmitter is shown diagrammatically in Fig. 4. An apparatus for the transmission of Wheatstone signals from cable code tape is schematically shown 45 in Fig. 2. A distributor of the standard type, consisting of a pair of transmitter rings 1 and 2 and a pair of operating rings 3 and 4 over which brushes are revolved synchronously by 50 means of a phonic motor (not shown), is used in connection with a step-by-step transmitter and a group of relays. The transmitter rings consist of a solid ring 1 and a segmented ring 2 made up of operating segments 5 and 7 and locking segments 6-6'. The operating rings 55 consist of a solid ring 3 and a segmented ring 4 made up of receiving segments 8 and 9, locking segments 10 and 11, and locking segments 12 and 13.

60 Whenever a Wheatstone dot (one positive element followed by one negative element) is to be transmitted, the transmitter operating magnet 14 is operated in the normal manner of operation for step-by-step transmitters by the 65 completion of a circuit from positive battery through the transmitter solid ring 1, the brushes 15, an operating segment 7, the transmitting operating magnet 14 to negative battery. The current through the operating magnet actuates 70 it, thus pulling the dot and dash transmitter tongues 16 and 17 to their spacing positions and away from their marking contacts. After the tongues 16, 17 have been pulled to spacing, the tape (not shown in Fig. 2, but shown in Fig. 4) 75 is stepped forward one center hole. This opera-

tion may be more clearly understood by reference to Fig. 4. When the brush passes from the operating segment 7, the operating magnet circuit is broken and the tongues are pulled upward by a spring. The dot and dash relay tongues have the peckers 18 and 19, respectively, at their free ends so arranged that either the dot or dash tongue may close its contact when the corresponding perforation appears in the cable code tape, that is, operating segment prior to 7 inserted a dot tape signal.

For instance, assume that a dot is to be transmitted. Then, only the dot pecker 18 enters a previously punched hole in the cable tape and the dot tongue closes its marking contact. When the brush 20 on the operating rings 3, 4 next comes to a receiving segment, such as 8, a circuit is established from positive battery through the operating winding of the locking relay 21, solid operating ring 3, brushes 20, receiving segment 8, through the tongue and spacing contact of the dot local relay 22, and then from the dot tongue 16 and marking contact of the dot portion of transmitter relay 14 to negative battery. This circuit from the operating winding of the locking relay 21 moves the tongue of relay 21 to its marking contact and thus establishes the circuit from positive battery through the operating winding of the line relay 23, through the tongue of the locking relay 21, to negative battery, operating the line relay 23 to marking and causing a dot pulse one half element long to be transmitted to the line. As the brush passes from the receiving segment 8 on to locking segment 10, a circuit is established from positive battery through the operating winding of the locking relay 21, the solid operating ring 3, brushes 20, the first locking circuit 10, through the spacing contact and tongue of the dash local relay 24, the tongue and marking contact of the locking relay 21 to negative battery. As the brush passes from the first locking segment 10, the circuit through the operating winding of the locking relay 21 is broken and this relay returns to its spacing contact, thus breaking the circuit of the operating winding of line relay 23 the tongue of which also returns to its spacing contact and begins to send out the negative element of the Wheatstone dot signal.

In the circuit described above, the locking relay 21 and, therefore, the line relay 23 are operated to their marking contacts for one element out of the two assigned to the dot impulse, so that a positive pulse and a negative pulse, each equal in length to one element, are transmitted for each dot perforation of the cable code tape. The result is a translation of the cable code dot into a Wheatstone dot. Simultaneously, segment 7 steps the tape, say, for a dash signal.

Whenever a space is to be transmitted, the transmitter is operated in the manner described above but, as there is no perforation in the tape for the space, neither the dot nor the dash contacts of the tape transmitter are closed, and, therefore, locking relay 21 and line relay 23 are held to their spacing contacts by the biasing circuit so that a space is transmitted to the line.

When a dash pulse is to be transmitted, the transmitter operating magnet 34 is operated in the normal manner by segment 7 and then released. Then the dash pecker 19 rises through a dash perforation in the cable code tape, and the dash tongue 17 of the transmitter relay 14 closes its contact. When the brushes 20 on the operating rings 3 and 4 reach the next receiving segment, say 9, a circuit is established from positive

battery through the operating winding of the locking relay 21, the operating solid ring 3, the brushes 20, receiving segment 9, the dash transmitter tongue 17 of relay 14, the operating winding 25 of the dash local relay 24 to negative battery. The current in this circuit operates the tongues of the locking relay 21 and the dash local relay 24 to their marking contacts. As the brushes 20 pass from the receiving segment 9 to locking segment 11, a circuit is established from positive battery through the operating winding of the locking relay 21, the solid operating ring 3, the brushes 20, segment 11, the locking winding 26 of the dash local relay 24, the operating winding 27 of the transmitter relay 28, the tongue and marking contact of the locking relay 21 to negative battery. The current in this circuit holds the locking relay 21 to its marking contact, holds the dash local relay 24 to its marking contact, and moves the transmitter relay 28 to its marking contact. As the brush 15 on the transmitter rings 1 and 2 passes from the operating segment 5 to the locking segment 6', a circuit is established from positive battery through the solid transmitter ring 1, the brushes 15, the locking segment 6', the marking contact and tongue of the transmitter relay 28, the operating winding 29 of the auxiliary locking relay 30, the locking winding 31 of the transmitter relay 28, the operating winding 33 of the dot local relay 22, the transmitter operating magnet winding 34 to negative battery. The current in this circuit moves the tongue of the auxiliary locking relay 30 to its marking contact, moves the tongue of the dot local relay 22 to its marking contact, holds the transmitter relay 28 to its marking contact, and holds the transmitter 14 in its operated position. As the locking segment 6' takes up the entire length between successive operating segments 5 and 7 on the transmitter rings 1 and 2, the transmitter 14 is held in its operated position during this entire time so that two cable code time intervals or four time elements elapse before the transmitter 14 is again released. Thus, while the cable code tape is being stepped by segment 7 to the next or, say, dash signal, the signal for a dot, as explained above, is simultaneously transmitted over circuits completed by rings 3 and 4; but, upon further rotation of the rings, when brush 20 makes its contact with segment 9, and while segment 6 is still covered by brush 15 (magnet 14 being, therefore, de-energized when the dot is being transmitted), and dash pecker 19 being on its marking contact, a circuit is completed, when brush 20 makes its contact with segment 9 and subsequently with segments 11 and 13, as above explained, for transmitting two elements of the Wheatstone dash. Although segment 5 simultaneously steps the tape forward one center notch, a locking circuit, previously established through the marking contacts of transmitter relay 28, is energized when brush 15 passes over segment 6', holding magnet coils 14 energized and, therefore, keeping the dot and dash peckers away from the tape and in inoperative positions until after segment 7 (assuming that the drawing Fig. 1 shows the rings completely) is passed over again and segment 6 is covered by the brush 15.

70 Thus the transmitter is halted or kept from transmitting, as far as signals punched on the Morse cable code tape are concerned, for one cable code time interval or two time elements for all dash perforations in the cable code tape. This makes possible the four time elements necessary to transmit a Wheatstone dash, e. g., two elements while segments 9, 11 and 13 are passed over by brush 20 and two elements while segments 8, 10 and 12 are passed over by brush 20. While the first two elements are being transmitted the last third of segment 6, segment 5, and the first two thirds of segment 6' are passed over by brush 15. While the second two elements are being transmitted the last third of segment 6', segment 7, and the first two thirds of segment 6 are passed over by brush 15. Thus, when segment 9 is again reached by brush 20, all the relays will be ready for the new signal, as explained above. In short, as the brushes on the operating rings pass from segment 11 to segment 13, a circuit is established from positive battery through the operating winding of the locking relay 21, ring 3, the brushes 20, segment 13, tongue and marking contacts of the auxiliary locking relay 30 through the tongue and marking contact of the locking relay 21 to negative battery. The current in this circuit holds the tongue of the locking relay 21 to its marking contact. As the circuit through segment 13 is not broken until the brushes are passed on to the next receiving segment, e. g., 8, the locking relay 21 and, therefore, the line relay 23 are both held to their marking contacts for the full length of time between successive receiving segments, namely, for two time elements, so that two positive impulses, each equal in length to one element, are transmitted to line. When the brushes pass from locking segment 13 on to the next receiving segment, e. g., 8, both the dot and dash transmitter tongues 16 and 17 are in their back position so that both their contacts are open. A circuit at this time, however, is established from positive battery through the operating winding of the locking relay 21, through the operating solid ring 3, the brushes 20, receiving segment 8, tongue and marking contact of the dot local relay 22 to negative battery. From this point on until the next receiving segment is reached, e. g., 9, the circuits function in the same manner as described for a dot transmitted from a dot perforation in the tape, namely, transmitting a positive element and a negative element to the line, thereby making, in all, three positive elements and one negative element which is the conventional Wheatstone dash.

Now, as the brushes 15 on the transmitter rings 1 and 2 pass from the locking segment, at the beginning of the supplementing Wheatstone dot signal, on to an operating segment, the circuit through the operating winding 29 of the auxiliary locking relay 30, the locking winding 31 of the transmitter relay 28, and the operating winding 33 of the dot local relay 22 is broken so that these relays return to their spacing contacts. The circuit through the transmitter operating magnets 34 and 34' is at this time established through the operating segment in the normal manner. When the brush passes from the operating segment, the transmitter 14 is released and allowed to set up the next combination to be transmitted while segments 10 and 12, for example, complete the dash signal.

Thus, whenever the circuits are operated by a dash perforation in the transmitter tape, the dash transmitter tongue starts the transmission to the line of the two positive impulses, each equal in length to one element, and also causes the circuits to be established for locking up the transmitter to subsequently keep it from stepping the

tape for an additional two element time period; thus causing it to pause for one cable code signal unit having two elements so that the dot termination of two additional elements, one positive and the second negative, can be supplied subsequently after the transmission of the first two positive impulses which both together occupy a time interval of two elements, making four elements all together.

- 10 Instead of the transmitter operating magnet, a cam may be used somewhat similar to that clearly shown in Patent No. 1,542,779 to W. C. Peterman, and indicated by numeral 22 of Fig. 1 of that patent. The afore-mentioned patent discloses a mechanical means which may be adapted or modified for operating the pecker pins 18 and 19.

Whenever it is desired to transmit cable code signals from Wheatstone tape, an inversion of the above method suggests itself. From the analysis given above it is apparent that dots and spaces which take up the same or equivalent time elements in both codes may be easily transmitted. The dashes, however, which take up two center holes in the Wheatstone tape and one center hole in the cable tape, require extra treatment. Thus, whenever a dash is to be transmitted in cable code signals from a Wheatstone tape, it is necessary to step the transmitter twice for each dash signal or to cause the transmitter 14 to step two teeth for each dash signal instead of the normal one tooth. Apparatus for performing this function is shown in Fig. 3.

In order to use Wheatstone tape with the cable code transmitter, the contacts of the dot tongue and dash tongue of the transmitter may be connected so that the dot pecker causes the tongue to put positive battery on receiving segments 8 and 9 when its associated pecker enters a hole in the lower part of the tape, while for a dash, the dash pecker alone enters a hole in the upper part of the Wheatstone tape (see Fig. 1).

Referring more particularly to Fig. 3, a commonly used apparatus is schematically shown for transmitting cable code signals from a cable code tape employing a step-by-step transmitter, but the circuit is modified to include an additional relay 50 which is operated only upon the transmission of dash signals when a Wheatstone tape is used to send cable signals. Corresponding parts of Figs. 2 and 3 are similarly numbered and, therefore, only the changed or new elements will be specifically enumerated below.

In order to more clearly describe the operation of the apparatus shown in Fig. 3, a typical signal will be transmitted. For instance, assume that a dot is to be transmitted; then the dot pecker 18 enters a hole in the lower part of the Wheatstone tape and the dot tongue 16 makes its marking contact, putting positive battery on segments 8 and 9 of operating ring 43. Although the dash pecker 19 enters the upper perforation in the Wheatstone tape, the closing of the dash marking contact by the dash tongue 17 produces no immediate result, as its circuit is opened at the spacing contact of the dot tongue. Dot tongue 16 still remains on its marking contact and brush 20 then passes over, say, receiving segment 8. Thus a circuit is closed through the operating windings of dot locking relay 51, dash locking relay 52, auxiliary transmitter relay 50, dot transmitting relay 54, and dash transmitting relay 55 to negative battery. The relays are all biased mechanically or electrically to spacing but,

upon completion of the above circuit, the tongues of dot locking relay 51 and dot transmitting relay 54 go to marking position, while relays 52, 50 and 55 are held to spacing position, thereby sending a positive impulse to the cable and simultaneously establishing a holding circuit for dot relay 54 from positive battery on marking contact and tongue of dot locking relay 51, brush 20, continuous ring 3, operating windings of relays 51, 52, 50, 54 and 55. This locking circuit maintains the dot transmitting relay on its marking contact for an interval of time equal in length to two positive impulses, each equal in length to one element of the Wheatstone code, thereby causing circuits to be established for locking the dot transmitting relay and causing it to transmit one positive cable code signal unit which has a time duration of two elements and, therefore, corresponds to a cable dot, on the basis of our analysis of the two codes. Operating segment prior to 44 positions a dot in the tape.

When a cable space is to be transmitted from a tape having a Wheatstone space, neither of the peckers is permitted to move upward through the tape, as there are no operating perforations for a space in a Wheatstone tape. As a result, all the relays are held on their spacing contacts by their biasing windings, and the cable is grounded for a time interval equal to one cable code signal unit or two elements of the Wheatstone code, thus producing an effect in the cable corresponding to a cable space unit.

Whenever a cable dash is to be transmitted over the cable from a Wheatstone tape having a Wheatstone dash perforated thereon, additional or auxiliary transmitter relay 50 is energized, in addition to other relays enumerated below. Thus on a dash signal, only the dash pecker 19 enters a perforation on the upper side of the Wheatstone tape. This causes the tongue 17 to prepare a circuit from negative battery, marking contact of the dash operating transmitter relay 14, tongue 17 of the dash operating transmitter relay 14, spacing contact and tongue 16 of dot operating transmitter relay 14 to one of the receiving segments 8 or 9. Then the circuit is continued through brushes 20, solid ring 3, operating windings of dot locking relay 51, dash locking relay 52, auxiliary transmitter relay 50, dot transmitting relay 54, dash transmitting relay 55, to positive battery. Since the current now courses through these circuits in a reverse direction, the tongues of dash locking relay 52, auxiliary transmitter 50 and dash transmitter relay 55 are held to their marking contacts, while the tongues of relays 51 and 54 are held to spacing. This results in the sending of a negative impulse to the cable and, simultaneously, in the establishing of a holding circuit for dash relay 55 from positive battery on operating winding 135 of relays 55, 54, 50, 52, 51, continuous ring 3, segment 57, tongue and marking contact of dash locking relay 52 to negative battery. This locking circuit maintains the dash transmitting relay on its marking contact for an interval of time 140 equal in length to two negative impulses, each equal in length to one element of the Wheatstone code, thereby causing circuits to be established for locking the dot transmitting relay and causing it to transmit one negative cable code signal 145 unit which has a time duration of two elements and, therefore, corresponds to a cable dot, on the basis of our analysis of the two codes.

The above follows, provided, of course, that segment 44 has previously stepped the Wheat-

stone tape to a dash signal. This has been assumed to be the case here. Thus, after brush 15 passes segment 44 (segments 8 and 56, say, are then transmitting a dot), transmitter 14 is ready for segment 9 to subsequently condition circuits for transmitting a cable code dash.

Whenever the relay 50 is operated, e. g., on all dash signals, and now we are assuming that segment 9 and associated relays will respond so as to transmit a dash, an intermediate auxiliary segment 45' on the transmitter operating ring 41 is connected in a parallel circuit with the normal operating segment 44', so that the transmitter 14 undergoes an additional stepping operation in order to advance the Wheatstone tape past the second Wheatstone dot perforation and in position for the perforation of the next signal in the Wheatstone tape. Thus segment 44 will advance the dash perforation for operation of the dash pecker, segment 9 will respond to the dash pecker's circuit, then segments 44' and 45' will advance the Wheatstone tape through the last perforation of the dash signal on to the Wheatstone tape and on to the next signal of the Wheatstone tape. Simultaneously with the last two stepping operations, holding or locking segment 57 will complete the transmission of the Morse cable code dash signal. Thus, immediately after this intermediate stepping by segment 44', the transmitter 14 is again operated through segments 45' and before the next receiving segment is in position, so that the second perforation of the dash signal is skipped and the transmitter is prepared for the next signal.

Another means for performing this same function is indicated in Fig. 4. In this case the additional relay, which operates only on dash signals, removes a back stop from the pawl which controls the stepping of the perforated tape, so that whenever this back stop is removed the pawl is allowed to step two teeth and, thus, the second perforation of the dash character is skipped.

Fig. 4 is particularly drawn to schematically show an additional modification of apparatus which may be used to step the Wheatstone tape two center holes whenever relay 50, described in connection with the above description of Fig. 2, is energized. With this apparatus the normal stop 60 is lowered whenever a dash signal is to be transmitted, so that stop 61 then limits the motion of pawl 65 of armature 62. This is accomplished whenever relay 50 marks so as to complete a circuit to energize coil 64 and cause the tape to be moved two center holes instead of one. Obviously, the spring biasing tongue 16 must be adjusted so as to make the tongue almost immediately responsive to the energization of operating magnet 34' so as to avoid any tearing of the tape by pecker 18. The apparatus shown is schematic only and is illustrative of one type of step-by-step transmitter adapted to operate with the apparatus shown in Fig. 3. Thus, a Wheatstone tape is shown moving from right to left. Magnet 34' corresponds to magnet 34' of Fig. 3, 18 is the dot pecker and 16 is the dot tongue, all of which correspond to apparatus indicated by similar numerals in Fig. 3.

It is to be noted in the above descriptions that

in Fig. 2 the dot pecker has been positioned so as to enter an upper or dot perforation in the Morse cable code tape, while in Fig. 3 the dot pecker has been positioned to enter a lower perforation of the two operative perforations in the Wheatstone code tape. The perforations entered by the dash pecker in both these cases are obvious. Although specific apparatus and methods for obtaining the translation of one code into another have been described above, I do not intend to be limited to the detailed or specific means of accomplishing this result herein disclosed, but only by the accompanying claims.

What is claimed is:

1. In an automatic telegraph system, a transmitting station, a receiving station, a line connecting said stations, a tape perforated with a three-element code including zero as one of its elements, a transmitter at said first station controlled by said tape, and means at said first station to feed the tape through one perforation in a predetermined time interval when a dot is transmitted, and to feed the tape through one perforation in twice the predetermined time interval when a dash is transmitted, to said receiving station.

2. In an automatic telegraph system, a transmitting station, a receiving station, a line connecting said stations, a tape perforated with a two-element code having plus and minus elements, a transmitter at said first station controlled by said tape, and means at said first station to feed the tape through one perforation in a predetermined time interval when a dot is transmitted, and to feed the tape through two perforations in an equivalent time interval when a dash is transmitted, to said receiving station.

3. In an automatic telegraph system, a transmitting station, a receiving station, a line connecting said stations, a tape perforated with a three-element code including zero as one of its elements, a transmitter at said first station controlled by said tape, stepping means for said tape, and a distributor having a set of segments, the odd segments of said set being adapted to cause said stepping means to feed the tape through one perforation in a predetermined time interval when a dot is transmitted, the alternate segments of said set being adapted to cause said stepping means to feed the tape through one perforation in twice the predetermined time interval when a dash is transmitted.

4. In an automatic telegraph system, a transmitting station, a receiving station, a line connecting said stations, a tape perforated with a two-element code having plus and minus elements, a transmitter at said first station controlled by said tape, stepping means for said tape, and a distributor having a set of segments, the alternate odd segments of said set being adapted to cause said stepping means to feed the tape through one perforation in a predetermined time interval when a dot is transmitted, the intervening odd segments of said set being adapted to cause said stepping means to feed the tape through an additional perforation only when a dash is transmitted.

MARION H. WOODWARD.
